L. D. WEST

AUTOMATIC DOOR CLOSER

Filed July 1, 1922

Patented May 15, 1923.

UNITED STATES PATENT OFFICE.

LEONIDAS D. WEST, OF DENVER, COLORADO.

AUTOMATIC DOOR CLOSER.

Application filed July 1, 1922. Serial No. 572,275.

To all whom it may concern:

Be it known that I, LEONIDAS D. WEST, a citizen of the United States, residing at the city and county of Denver and State of Colorado, have invented certain new and useful Improvements in Automatic Door Closers; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to door closers of the type usually employed on heavy doors to gradually and gently close the same.

It is well known that doors, unless special means is provided to prevent it, will close with a slam, which subjects the door and the hinges to excessive strains which damage the structure and cause a great deal of disturbance. When the doors are glazed, as is usually the case in office buildings, the sudden closing of the door will frequently break the glass.

To prevent the door from remaining open and to cause it to close slowly and gently, it is customary to equip each door with a heavy spring that is so tensioned as to constantly tend to close the door and also to combine the spring with a dash pot that will retard the closing to any degree desired.

It is the object of this invention to produce an improved closing means that shall be of neat and substantial design; which can readily be applied to any door; which shall be provided with readily accessible means for timing the closing of the door and which shall also have an accelerator that will come into play just as the door is about to close, so that the entire force of the spring will come into play in operating the bolt of the lock as the door closes.

In order to attain the objects of my invention, I employ a closer constructed as will be hereinafter described, reference being had to the accompanying drawing in which

Fig. 1 is a section taken on line 1—1,

Fig. 2;

Fig. 2 is a section taken on line 2—2, Fig. 1, and shows the dash pot cylinder in elevation, with parts thereof broken away to better show the construction;

Fig. 3 is a perspective view of a portion of

a door and door frame showing my closer in place;

Fig. 4 is a transverse section taken on line 4—4 Fig. 2;

Fig. 5 is a view of a portion of a door and door frame showing my closer connected to the door casing and to the door; and

Fig. 6 is a section showing a modified form of valve.

The same reference numbers will be used 65 to indicate the same parts throughout the several views.

Numeral 1 represents a door which is secured by means of hinges 2 to a door frame 3. My improved closer which I designate 70

as a whole by numeral 4 is hingedly connected to the door frame or casing and secured to a bracket 5 which is fastened to the door. Referring now more particularly to Figs. 1 and 2, numeral 6 represents a 75 cylindrical member of brass or similar material whose ends are closed by screw caps 7 and 8. Cap 7 has a member 9 near one side thereof; this member cooperates with part 10 to form a hinge whose pintle is formed 80 by screw 11. Cap 7 is provided with outwardly projecting ears 12 into which is threadedly secured pipes 13, in the manner shown most clearly in Fig. 2. Hooks 14 have their ends extending through the walls 85 of the ears of cap 7 and are provided with nuts 15. Secured within the tubes 13 are springs 16 whose ends are fastened to hooks 14. The purpose and function of these

90 springs will appear as the description proceeds. Cap 8 is provided with a central boss 17 which cooperates with the threaded cap 18 to form a packing box for the tubular piston rod 19. Within the cylinder 6 is a piston 20 of brass or any other suitable material. 95 Piston 20 has a groove 21 about its periphery for the reception of packing material. On the piston rod side of piston 20 I provide an integral lug 22 which has its ends connected to the piston 20 and its central portion 100 spaced therefrom. A hole 23 is bored through member 22 in alignment with the center of the piston 20, and the piston rod 19 is threadedly connected thereto. A hole 105 24 is provided in the center of piston 20 and is provided on one side with a valve seat 25 which cooperates with a correspondingly curved valve member 26. A short rod 27 is threadedly connected with the valve 26 and has its forward end extending into the 110

tubular piston rod 19, while its rear end is slidably connected with a bracket 28. Valve 26 has a rearwardly extending tubular portion 29 whose inside diameter is considerably larger than the rod 27. A spring 30 encircles the rod 27 and is partly enclosed by the tubular member 29. Rod 27 forms a guide for the valve 26 and assures that it will always correctly seat while the spring 30 constantly tends to maintain the valve closed. The tubular portion 29 extends rearwardly so as to leave only a small space between its end and the inside of the bracket 28, and therefore serves as a stop for limiting the opening of the valve. A yoke piece 31 has two holes 32 which are threaded and adapted to receive the threaded end of pipe 33 which telescopes on pipe 13, as shown in Figs. 1 and 2. Hooks 34 pass through the holes in the yoke 31 and engage the end of the spring in a manner similar to that explained in connection with hooks 14. The forward end 35 of piston rod 19 extends a considerable distance beyond the outer surface of yoke 31, and has threadedly secured thereto a nut 36 which cooperates with the end of pipe 19 to form a packing box. A rod 37 extends through the tubular piston rod 19 and is of such length that its inner end contacts with the end of rod 27. The outer end of rod 37 is threaded as indicated by numeral 38, and these threads cooperate with corresponding threads in the nut 36. Secured to the end of rod 37 is a knurled knob 39 by means of which the rod 37 may be rotated. The rod 37 and knob 39 form what I term a "timer" or the means whereby the rate of operation is adjusted. It is evident that if rod 37 is screwed inwardly, its end will abut the end of rod 27 and serve as a stop for the latter, and by moving the rod 37 to the left, it will stop the valve from becoming entirely closed; this leakage space can be made large or small by adjusting the position of the rod 37. Secured to the yoke 31 is a rod 40 which has a perforated head 41 which engages the bracket 5, which is secured to the door and is held in place thereon by the screw 42.

When the closer is secured to the door, in the manner shown in Fig. 3, it is evident that when the door is opened the bracket 5 to which the rod is pivoted will pull the yoke 31 to the right and tension the springs 16, which will then exert a force tending to close the door.

It is my intention to have the space within the cylinder 6 filled with a liquid such as lubricating oil or kerosene, or any other suitable fluid. It is apparent that when the piston is moved to the right by the opening of the door, that the liquid will flow through the hole 24 past the valve 26, which will yield to pressure exerted in this direction. When, however, the door begins to close, the

piston will have to move towards the left and this can only take place as fast as the liquid can pass from the left hand chamber to the right hand chamber. In order to permit the piston to move towards the left, the valve is held from seating by the action of rod 37, in the manner above explained. In order to accelerate the movement towards the closing of the door, I provide a by-pass or accelerator 43 which can be adjusted by means of a valve 44. It is evident from an inspection of Fig. 2 that as soon as the piston passes the opening 45 that the liquid can be displaced from one side to the other through the by-pass, and in this manner the rate of closing can be accelerated towards the end of the stroke.

In Fig. 5 I have shown how the closer may be attached to the inside of the door frame, and for this purpose the hinge member 10 is replaced by a crow-foot 46 upon which the closer pivots. All the other parts of the closer remain the same.

In Fig. 6 I have shown a modified form of valve construction in which the rod 37 is provided with a conical point 37^a which passes through a cooperating hole in the valve 26. The rod 27 is omitted as the end 37^a serves as a guide to assure the proper seating of the valve. The rate of closing is adjusted by moving the rod 37 to the right or to the left. As the rod is moved towards the right, a larger space is left between the sides of the hole and the end 37^a, with a corresponding increase in the speed of closing.

From the above it will appear that I have provided a simple and efficient door closer that can be easily manufactured and readily installed, and which can be conveniently adjusted as to its speed of closing.

Attention is called to the fact that the end of member 40 is threaded for a considerable distance and that by rotating the same the tension of the springs 16 can be adjusted.

Having now described my invention, what I claim as new is—

1. In a device of the class described, in combination, a cylinder, means for closing both ends thereof, a piston slidable in said cylinder, means for reciprocating the piston comprising a tubular rod extending through the closure in one end of the piston, a valve in said piston, means for normally holding said valve in closed position, and means passing through the tubular rod for controlling the flow of liquid from one side of the valve to the other.

2. In a device of the class described, in combination, a cylinder, caps closing the ends thereof, a tubular rod passing through one of said caps into the cylinder, a piston within said cylinder and connected to the end of said tubular rod, a valve cooperating with said piston and adapted to let liquid pass in one direction only, a spring for nor-

5 mally holding said valve in closed position, means whereby a liquid may pass from one side of the piston to the other in the direction opposed by the valve, and means extending through the tubular rod for controlling the last named means.

3. In a device of the class described, in combination, a cylinder, caps closing the ends thereof, a tubular rod passing through 10 one of said caps into the cylinder, a piston within said cylinder and connected to the end of said tubular rod, said piston having a central opening provided on one side with a valve seat, a bracket secured to the side 15 having the valve seat, a valve cooperating with said seat, a spring abutting its ends against said bracket and said valve and tending to hold the latter against said seat whereby liquid will be permitted to pass 20 through said piston in one direction only, means permitting liquid to pass in the opposite direction, and means passing through the tubular rod for adjusting the said last named means.

25 4. In a device of the class described, in combination, a cylinder, caps closing the ends thereof, a tubular rod passing through one of said caps into the cylinder, a piston within said cylinder and connected to the 30 end of said tubular rod, said piston having a central opening provided on one side with a valve seat, a bracket secured to the side having the valve seat, a valve cooperating with said seat, a spring abutting its ends 35 against said bracket and said valve, and tending to hold the latter against said seat whereby liquid will be permitted to pass through said piston in one direction only, means permitting liquid to pass in the opposite direction, means passing through the 40 tubular rod for adjusting the said last named means, and a pipe opening into said cylinder at two spaced points near one end thereof whereby the movement of the piston 45 will be accelerated near the end of its movement.

5. In a device of the class described, in combination, a cylinder, caps closing the ends thereof, a tubular rod passing through 50 one of said caps into the cylinder, a piston within said cylinder and connected to the end of said tubular rod, said piston having a central opening provided on one side with a valve seat, a bracket secured to the side 55 having the valve seat, a valve cooperating with said seat, a spring abutting its ends against said bracket and said valve, and tending to hold the latter against said seat whereby liquid will be permitted to pass 60 through said piston in one direction only, means permitting liquid to pass in the opposite direction, means passing through the tubular rod for adjusting the said last named means, a pipe opening into said cylinder at two spaced points near one end 65

thereof, whereby the movement of the piston will be accelerated near the end of its movement, and means for adjusting the effective opening through said pipe.

6. A door closer, comprising in combination, a cylinder, a cap secured to each end thereof, a tubular rod extending through one of said caps, a stuffing box for making a tight joint between said cap and said rod, said tubular rod having its outer end threadedly connected to a yoke piece, a rod slidably connected with said tubular rod, a stuffing box on the outer end of said tubular rod and cooperating with said slideable rod, a piston within the cylinder connected to the inner end of said tubular rod, a valve in said piston for permitting a liquid to flow in one direction only, means for permitting a liquid to flow in the opposite direction, said means being adjustable by means of the rod that is slidably connected with the tubular rod.

7. A door closer, comprising in combination, a cylinder, a cap secured to each end thereof, a tubular rod extending through one of said caps, a stuffing box for making a tight joint between said cap and said rod, said tubular rod having its outer end threadedly connected to a yoke piece, a rod slidably connected with said tubular rod, a stuffing box on the outer end of said tubular rod and cooperating with said slideable rod, a piston within the cylinder connected to the inner end of said tubular rod, a valve in said piston for permitting a liquid to flow in one direction only, means for permitting a liquid to flow in the opposite direction, said means being adjustable by means of the rod that is slidably connected with the tubular rod, and tension springs connecting the yoke with one of said caps.

8. A door closer, comprising in combination, a cylinder, a cap secured to each end thereof and adapted to close the same, one of said caps having a hinged portion and a pair of lugs formed integral therewith, the other cap having a central threaded stud with an axial opening therethrough, a tubular piston rod passing through the opening in said stud, a nut cooperating with said stud and adapted to form therewith a packing box, a piston within said cylinder and threadedly connected with one end of said piston rod, and a yoke piece connected to the other end, the last named end extending through said yoke piece, a nut threadedly connected to said extending end, a rod slideable within said piston rod and threadedly connected to said last named nut, a pair of telescoping tubes joining the lugs on the cap and the yoke, springs within said tubular members, a valve in said piston, yielding means to hold the valve in closed position, means to permit a liquid to pass through the piston in a direction opposed to said valve, and means operated by the rod with-

in the tubular piston rod for controlling the last named means.

9. A door closer, comprising in combination, a cylinder, a cap secured to each end thereof and adapted to close the same, one of said caps having a hinged portion and a pair of lugs formed integral therewith, the other cap having a central threaded stud with an axial opening therethrough, a tubular piston rod passing through the opening in said stud, a nut cooperating with said stud and adapted to form therewith a packing box, a piston within said cylinder and threadedly connected with one end of said piston rod, and a yoke piece connected to the other end, the last named end extending through said yoke piece, a nut threadedly connected to said extending end, a rod slideable within said piston rod and threadedly connected to the last named nut, a pair of telescoping tubes joining the lugs on the cap and the yoke, springs within said tubular members, a valve in said piston, yielding means to hold the valve in closed position, means to permit a liquid to pass through the piston in a direction opposed to said valve,

means operated by the rod within the tubular piston rod for controlling the last named means, and a tubular member opening into the piston at two spaced points near one end thereof.

10. A door closer, comprising in combination, a cylinder, a piston within the cylinder, caps for closing the ends of the cylinder, a tubular piston rod extending through one cap and having its inner end connected to the piston, liquid in said cylinder, a valve in said piston, said valve being yieldingly held in place and adapted to let the liquid pass in one direction only, an opening through which the liquid may pass in the direction opposite to that in which it is permitted to pass by the valve, means comprising a bar passing through the tubular piston rod for controlling the extent of said opening, means for pivotally securing said cylinder to a door frame, means for connecting said piston rod with a bracket secured to a door, and spring means tending to maintain the door in closed position,

In testimony whereof I affix my signature.
LEONIDAS D. WEST.
